(57) **CLAIM**

The ornamental design of a fire log handling apparatus, as shown and described.

DESCRIPTION

FIG. 1 is an isometric side view of a fire log handling apparatus incorporating our new design;

FIG. 2 is a right side elevation view thereof;

FIG. 3 is a front end elevation view thereof;

FIG. 4 is a top plan view thereof;

FIG. 5 is a left side elevation view thereof;

FIG. 6 is a rear end elevation thereof; and,

FIG. 7 is a bottom plan view thereof.
